UNITED STATES PATENT OFFICE.

JOHN RENFREW DEAN, OF NEW BRITAIN, CONNECTICUT.

DESIGN FOR A PADLOCK.

No. 39,745.

Specification for Design.

Patented Jan. 5, 1909.

Application filed May 7, 1908. Serial No. 431,542. Term of patent 7 years.

To all whom it may concern:

Be it known that I, JOHN RENFREW DEAN, citizen of the United States, residing at New Britain, Hartford county, Connecticut, have invented a new, original, and ornamental Design for Padlocks, of which the following is a full, clear, and exact description.

This invention relates to a new, original and ornamental design for padlocks.

The design comprises a padlock having a main body portion of the outline in the drawing wherein the distinguishing features comprise rounded bulging lower corners for said body portion; said body being sur-

mounted with an arch, the sides of which project for a short distance vertically from said body as shown in the drawing. The body portion also bears thereon the representation of an Indian's head.

The figure is a face view of the padlock showing the design.

I claim

The ornamental design for a padlock as shown and described.

JOHN RENFREW DEAN.
